HAIR BRUSH AND COMB COMBINATION

Martin Newman, 1203 N. Sweetzer 90060, and Alvin L. Frankel, 6038 W. 75th St. 90045, both of Los Angeles, Calif.

Filed Dec. 13, 1972, Ser. No. 314,836

Term of patent 14 years

Int. Cl. D4—02

U.S. Cl. D4—21

FIG. 1 is a perspective view of a hair brush and comb combination showing my new design;

FIG. 2 is a front end view of the design shown in FIG. 1;

FIG. 3 is a rear end view of the design shown in FIG. 1;

FIG. 4 is a side elevation of the design shown in FIG. 1;

FIG. 5 is a top view of the design shown in FIG. 1; and

FIG. 6 is a bottom view of the design shown in FIG. 1. I claim:

The ornamental design for a hair brush and comb combination, substantially as shown.
